(57) **CLAIM**

The ornamental design for an electronic display device, as shown and described.

DESCRIPTION

FIG. 1 is a rear view of the electronic display device showing my design;

FIG. 2 is a left side view thereof;

FIG. 3 is a top view thereof;

FIG. 4 is a right side view thereof;

FIG. 5 is a front view thereof;

FIG. 6 is a bottom view thereof;

FIG. 7 is a top perspective view thereof;

FIG. 8 is a left side view of a second embodiment of an electronic display device showing my design;

FIG. 9 is a top view of the second embodiment;

FIG. 10 is a right side view of the second embodiment;

FIG. 11 is a front view of the second embodiment;

FIG. 12 is a bottom view of the second embodiment;

FIG. 13 is a rear view of the second embodiment; and,

FIG. 14 is a top perspective view of the second embodiment.
